SPARK PLUG

Felix M. Anthony, Piedmont, Calif., assignor of
one-fourth to Kenneth C. Gillis and one-fourth
to Darrell B. Edwards, both of Oakland, Calif.

Application July 17, 1931, Serial No. 551,334

1 Claim. (Cl. 123—169)

This invention relates to improvements in spark plugs and more particularly to the electrode terminals of spark plugs for internal combustion motors.

5 The principal object of the invention is to provide a spark plug that will fire at high working pressures in the modern high speed, high compression automobile motors, at every ignition cycle.

10 Another object is to provide a "spark" of large volume discharged between terminals of considerable area to create a flame-like ignition for the propagation of combustion in the firing chamber.

15 Other objects and advantages will appear as the description progresses.

In this specification and the accompanying drawing the invention is disclosed in its preferred form. It is to be understood, however, 20 that it is not limited to this form because it may be embodied in other forms within the purview of the claim following the description.

In the one sheet of drawings:

Fig. 1 is a vertical section of a spark plug 25 constructed in accordance with this invention.

Fig. 2 is an end view of the same from below.

Fig. 3 is a fragmentary detail side view in cross-section of a modified form of ground electrode.

30 Figs. 4 and 5 are horizontal section and plane views respectively of the grid firing surface of the electrodes.

In detail the construction illustrated in the drawing comprises the outer shell 1, having the threaded neck 2 for engaging the cylinder head 35 of the motor, not shown. The shoulder 3 provides for compressing the usual gasket against the cylinder head when the shell is screwed therein by means of the hexagonal portion 4.

The center bore of the top portion is internally 40 threaded to receive the threaded bushing 5, having the hexagonal head 6.

The dielectric core 7 is usually formed of porcelain, compressed mica or other refractory material. This core extends through the shell 1 and 45 is held in fixed position by screwing down the bushing 5 which forces the core against a suitable shoulder provided within the shell 1.

The center electrode 8 extends entirely through the core and engages the conventional terminal 50 fixed in the end of the core. The inner end of the electrode is swaged to form the head 10, the plane of which is transverse to the axis of the electrode. The electrode projects sufficiently to locate the head beyond the end of the core 7, and beyond 55 the end of the shell also. The mechanical char-

acteristics of spark plugs vary with the type of motor in which they are used, which modifications are applicable to the present invention by those skilled in the art, without departing from the spirit of the invention.

5 The ground terminal 11 is fixed in the edge of the shell in the usual manner and bent at 12 to bring the end 13 in juxtaposition to the head 10. The end 13 is flattened to form a plate in juxtaposition to the head with its plane parallel with the plane of the head 10.

The opposed surfaces of the head 10 and plate 13 are provided with a multiplicity of depressions 14 and 15 respectively, which form a pair of grid-like surfaces 16—17 on the whole areas of the opposed faces of said head 10 and plate 13. Both surfaces are preferably of substantially the same area.

Much of the success of the present invention 20 is ascribable to this grid surface in combination with the parallel planes of these heads and the increased areas of each. Before a spark can bridge the gap, the gas lying between must be ionized. With the conventional type of gap these ions are blown away with the incoming gas 25 stream of the intake cycle, while in this invention, a large number of ions are retained in the recesses of the grid surface. As a consequence, less potential is necessary, and a greater volume of current is permitted to flow across the 30 gap. As the heat increases with the increase of current flowing, a much hotter spark is produced, which is necessary when typical blended gasolines are used.

The value of the above mechanical combination 35 becomes apparent when viewed in connection with the operation of the ignition system. The instant the coil's secondary system becomes active, a strong "electric field" is produced between and around the points of the plug and the air and 40 gas lying in this field become ionized and the current in a spark is carried across the gap by these ions or charged particles. These ions are usually present in any gas in very small numbers, and permit the passage of an extremely 45 small current only. This current is so small that ordinarily, air, or any other gas, can be considered as a perfect insulator. But if these ions are present in an "electric field" between two charged electrodes, they are affected by mechanical forces and will move along the axis of the field. This movement necessarily produces collisions with other molecules, and when the ions have acquired sufficient momentum, the collision causes disruption of a neutral molecule with 50 55

the production of two new electrically charged ions of opposite sign. This action continues to carry on under the influence of the electric field, and collisions with other molecules produce a further supply of ions at an ever increasing rate, and when sufficient ions become available, the energy of collision materializes as light and heat, and the current passes across the gap as a spark. It follows, therefore, that any condition, such as 10 the opposed grid surfaces, that will trap and retain a considerable quantity of such ions will contribute to the improved operation of the spark plug, especially under high pressure conditions.

Heretofore, it has been the practice to merely 15 arrange a "gap" between the wire electrodes of spark plugs, and where an enlarged head is used it has been confined to one electrode without varying the other to any extent. So far as I am aware I am the first to arrange two flat, grid 20 surfaced planes in parallel relation, to form a spark gap in the spark plug, as shown.

The phenomena incidental to the electrical discharge across the gap at X differs from that of 25 any other form of plug available for comparative tests. Most of the plugs show the usual flash across the conventional terminals. Such sparks were effective under the conditions existing in the older types of internal combustion motors. In the modern high compression, high speed 30 motors with multiple cylinders, the ignition interval is so short and frequent that the spark plug must be intensely responsive or the spark will be quenched by the highly compressed fuel,

or the current will find a path of less resistance than the gap.

In actual visual pressure tests the best spark plugs now available in the open market will begin "skipping" at from 50 to 65 pounds pressure per square inch and will fail entirely at 70 to 75 pounds. Under the same conditions the present spark plug continues to "fire" at pressures up to and above 150 pounds pressure.

The discharge between the grid surfaces of 10 the head 10 and plate 13 is in the nature of a flaming zone that never fails to propagate a flame in the compressed fuel, even when a weaker "spark" of the old type will "jump" through the fuel without producing complete combustion, or 15 fail to spark at all.

It is desirable to keep the bend 12 below the level of the spark gap to drain accumulated oil away from the gap between the terminals.

The modifications shown in Fig. 3 is only in 20 the mechanical construction of the ground terminal. All corresponding parts are identified with the same reference characters with the addition of X to indicate the modifications.

Having thus described this invention what is 25 claimed and desired to secure by Letters Patent is:

A spark plug having insulated electrodes having 30 confronting terminal surfaces arranged in parallel juxtaposition and having inter-spaced depressions therein so as to form a flat grid-like lattice surface above the bottom of the depressions.
